UNITED STATES PATENT OFFICE.

NEIL SINCLAIR, OF OAKLAND, CALIFORNIA, ASSIGNOR TO RIP VAN WINKLE WALL BED COMPANY, INC., OF OAKLAND, CALIFORNIA, A CORPORATION OF CALIFORNIA.

FOLDING BED.

Application filed March 27, 1924. Serial No. 702,214.

My invention has for its object the combination of a bed, a wall and a receptacle, and supporting and operating connections therebetween whereby the bed may be 5 swung from one side of the wall into the receptacle or may be withdrawn from the receptacle and positioned against the wall.

Other objects I accomplish by the employment of a plurality of pivoted means 10 being mounted on one side of the receptacle and also upon the bed respectively, and connecting and supporting arms therebetween whereby the bed is pivoted about the ends 15 of the arms and the arms are pivoted to the side of the receptacle.

By referring to the accompanying drawing and specifications my invention will be made clear.

Fig. 1 is a plan view showing the bed diagrammatically in the full closed position in 20 the closet or receptacle.

Figs. 2 to 5 inclusive are similar to Fig. 1 with the bed in successive advanced positions as it is swung from the closet position 25 of Fig. 1 to the fully opened position of Fig. 5, when the upended bed is fully in the room and ready to be let down.

Fig. 6 is a plan view similar to Fig. 2 but 30 with the parts shown somewhat more in detail.

Fig. 7 is a side elevation of the lower pivot and the swinging arm and a portion of the bed frame, and is taken on the line VII—VII of Fig. 6.

Fig. 8 is similar to Fig. 6 with the bed 35 fully swung into the room corresponding with the position shown in Fig. 5.

Fig. 9 is a side view taken on the line IX—IX of Fig. 6.

Fig. 10 is a side view of the bed in its 40 upended position when fully swung into the room in accordance with Figs. 5 and 8 and also shows the bed when swung down into final position in dotted lines from the upended position in full lines.

Throughout the figures similar numerals 45 refer to identical parts.

The wall of a room is shown by the numerals 1 and 2 respectively from which is 50 opened a receptacle or closet 3 having inner walls 4, 5 and 6, respectively and preferably also a door 7 normally closing the said closet.

Mounted either on or adjacent to the wall 55 6 is the pivot support 8 carrying the arm 9

and in line therewith a second pivot support 10 carrying the arm 11. These supporting arms are rigidly fixed to the connecting bar 13, whereby they are caused to move in synchronism about the pivots 12 60 and 14. Pivoted on the bar 13 is the head piece 15 of a conventional folding bed. A spacing arm 16 pivoted at 17 adjacent to the wall 6 compels the movement of the bed member 15 as the arms 9 and 11 and 65 rod 13 are swung about the pivots 12, 14. See Figs. 6, 7, 8.

The path of movement of the rod 13 is shown by the arc 18, Fig. 3, and the arc described by the arm 16 is shown at 19. 70

It will now be seen that as the bed swings from the position at Fig. 1 to the position of Fig. 3, the arms 9 and 16 move substantially through the same angle and that thereafter during the movement shown in 75 Figs. 4 and 5 the arm 9 moves but slightly, whereas the arm 16 moves through substantially 90 degrees. There will therefore be a total movement of the arm 9 of substantially 180 degrees and of the arm 16 of 270 degrees, when the bed is shifted from the position of Fig. 1 to the position of Fig. 5.

To prevent the arms 9 and 11 and rod 13 becoming buckled upon the dead center when in line with pivot 17, I introduce the 80 stop lug 20 integral with the rod 13, against which the arm 16 contacts. See Figs. 3, 5, 8. In the extreme position of Fig. 8 and when the bed is swung out in the direction of the arrow 21 towards its closing direction, the 85 arm 16 through contacting with the lug 20, forces the rod 13 in a closing direction clear of pivot 17 and away from the dead center.

In place of the lug 20 the arms and parts 90 may be so proportioned that instead of the rod 13 arriving over the dead center of pivot 17, its final position may be just outside thereof, thus insuring its returning movement clear of the dead center when the bed is swung in the direction 21. 100

When the bed arrives at the final position of Figs. 5, 8 and 10, the folding portion 22 is turned down, shown by dotted lines in Fig. 10, thus making the bed available for use in the room. When the bed is swung 105 entirely into the closet or receptacle 3 as shown in Fig. 1, the door 7 is closed, totally obscuring closet and bed contained therein. The closet walls 4 and 5 are always accessible regardless of whether the bed is in the 110

position of Fig. 1, or Fig. 5 or any of the intermediate positions, access being readily attained as through the space indicated by the arrow 23, Fig. 5.

5 I claim:—

1. A wall bed mounting comprising a pair of horizontally disposed supporting arms vertically pivoted at one end each to a fixed point adjacent a closet side wall and pivotally supporting the bed at the other ends adapting the bed to swing outwardly from a position within the closet substantially parallel and adjacent to said side wall to an out position at right angles therewith extending beyond said side wall substantially half the width of the bed, and a guiding arm pivoted similarly to the pivoting of said arms insuring such movement of the bed and said guiding arm being provided with a relatively short offset inner end whereby its fixed pivotal point is kept within the closet adjacent the outer corner of the wall with the arm entirely clearing the corner of the wall when the bed is in out position and the main body of the arm extends substantially at right angles away from the closet.
- 10 2. A wall bed mounting comprising a pair of horizontally disposed supporting arms vertically pivoted at one end each to a fixed point adjacent a closet side wall and pivotally supporting the bed at the other ends adapting the bed to swing outwardly from a position within the closet substantially parallel and adjacent to said side wall to an out position at right angles therewith extending beyond said side wall substantially half the width of the bed, and a guiding arm pivoted similarly to the pivoting of said arms insuring such movement of the bed and entirely clearing and overlapping the outer corner of said wall in the out position of the bed.
- 15 3. In a structure as specified in claim 1 one of said supporting arms being arranged to contact said guiding arm in the out position of the bed for limiting the relative movement of the arms.
- 20 4. In a structure as specified in claim 1 all of said arms being positioned between the bed and wall and pivoted at points lying within the outer corner of the wall.
- 25

adapting the bed to swing outwardly from a position within the closet substantially parallel and adjacent to said side wall to an out position at right angles therewith extending beyond said side wall substantially half the width of the bed, and a guiding arm pivoted similarly to the pivoting of said arms insuring such movement of the bed and said guiding arm being provided with a relatively short offset inner end whereby its fixed pivotal point is kept within the closet adjacent the outer corner of the wall with the arm entirely clearing the corner of the wall when the bed is in out position and the main body of the arm extends substantially at right angles away from the closet.

35 3. In a structure as specified in claim 1 one of said supporting arms being arranged to contact said guiding arm in the out position of the bed for limiting the relative movement of the arms.

40 4. In a structure as specified in claim 1 all of said arms being positioned between the bed and wall and pivoted at points lying within the outer corner of the wall.

45 NEIL SINCLAIR.
